UNITED STATES PATENT OFFICE.

GUSTAVE O. DEGENER, OF HARTFORD, CONNECTICUT, ASSIGNOR TO ROYAL TYPE-WRITER COMPANY, INC., OF NEW YORK, N. Y., A CORPORATION OF NEW YORK.

TYPEWRITING MACHINE.

Application filed August 31, 1923. Serial No. 680,405.

To all whom it may concern:

Be it known that I, GUSTAVE O. DEGENER, a citizen of the United States, residing at Hartford, in the county of Hartford and State of Connecticut, have invented certain new and useful Improvements in Typewriting Machines, of which the following is a specification.

This invention relates to typewriting machines in which the type bars are moved to the printing point by key levers operatively connected with the type bars and are returned to normal position by springs of various kinds. Machines of this class have been provided with means for varying the tension of the return springs.

According to my invention, I provide novel means for varying the relation of the springs to the key levers which, without changing the tension of the springs, varies within desired limitations their effective force on the type action. Another feature of my invention resides in a latch carried by each key lever which operates momentarily to lock or hold the connected type bar in normal or retracted position immediately after it has reached such position but which automatically releases itself immediately after the actuated key has been released by the operator, and as soon as the type bar has reached its rest.

In carrying out my invention, I provide each key lever with a spring which is attached to a frame mounted in the machine below the type bars. This frame carries all the springs and is provided with means for adjusting its position fore and aft of the machine in such manner that the connections between the springs and the key levers is varied relatively to the fulcrums of the key levers and thus the lengths of the arms of the key levers relatively to the springs is adjusted so that the effective force of the springs is varied.

Each key lever is provided with a latch which is adapted to engage a stationary part of the machine frame and which serves to momentarily hold the connected type bar in its retracted position against rebound when first brought to this position. The latch is so constructed and mounted that while it momentarily locks the connected key lever and therefore the connected type bar, it immediately thereafter, by its own weight or

gravity, returns to its normal unlatched position.

My improvements are illustrated in the accompanying drawings which are fragmentary views of a portion of a typewriting machine of the Royal type with my improvements applied. I would say, however, that my improvements may be applied to type actions for typewriting machines of other kinds. I have merely illustrated mechanism of well known and approved construction to which my improvements are particularly applicable.

Figure 1 is a fragmentary view in longitudinal section of so much of the mechanism of a typewriting machine as is necessary to illustrate how my improvements are applied thereto.

Figure 2 shows a transverse section and illustrates particularly the construction of the spring-carrying frame forming part of my improvements.

Figure 3 is a fragmentary plan view of the springs and their frame.

Figure 4 is a detail view, showing how a latch constructed in accordance with my invention is applied to a key lever, and how it operates to hold the associate type bar against rebound.

In Figure 1 the latch is shown in its unlocked position. In Figure 4 the latch is in active operation which, as before stated, is momentary.

Figure 5 is a perspective view of the latch member.

A part of the machine frame is indicated at A. B indicates a type bar, C a key lever, and D a rest or stop for the type bars when in normal or retracted position. a, b, c illustrate connections between the key levers and the type bars. These may be of any approved construction. Each type bar is pivotally mounted at B' and the key levers are pivotally mounted to move about a common axis d in a transverse rail or bracket U carried by the main frame.

The key levers are held in their normal, raised position by springs E carried by a frame F which is adjustable fore and aft of the machine in a manner hereinafter described. Preferably the frame F is Z-shaped in cross section, the upper forwardly extending part of the frame supporting the springs and the frame is supported by pins G ex-

- tending rearwardly from the rail U. These pins not only serve to support the frame but they also serve to hold it in proper alignment and to guide it while being moved.
- 5 Each spring E has a horizontal upper part having at its front end a downwardly extending looped part e which extends under a key lever and each such spring is coiled at e' to increase its resiliency. The rear end of 10 each spring is rigidly secured to the frame F and preferably each spring is made of wire so that conveniently the two springs for two adjacent key levers may be made from a single piece of wire as shown. Each pair of 15 springs E may thus be secured to the frame F by a single screw H. This is the preferred way of constructing the springs and of attaching them to the frame but other devices for this purpose are contemplated.
- 20 When a key lever is depressed it acts against the force of a spring E and when the key lever is released by the operator the spring serves to return the key lever and the connected type bar to normal position.
- 25 In order to vary the effective force of the springs on the type action without changing the tension of the springs, I provide means for adjusting the leverage of the key levers with relation to the springs; that 30 is, for changing the length of the arms of the key levers relatively to the engaged ends of the springs and the fulcrum of the levers. Preferably this is done by a rod K extending through the back of the main frame 35 and provided with a screw thread k engaging the frame F. The rod is provided with a knob k' by means of which it may be turned to move the frame fore and aft of the machine. In order to strengthen the 40 frame and to guide it, I have provided said frame with an arm L extending longitudinally rearwards under a roller m on a bracket M attached to the frame A. By these devices the spring-carrying frame may 45 be adjusted to the desired extent to vary the relation of the springs to the key levers. Preferably the frame F is formed with a toothed flange f for holding the wire springs in proper position.
- 50 It will be observed that the springs E have front ends which extend under the key levers and they have a sliding engagement with said levers. The coils e' are 55 preferably located close to the front of the frame F and these coils have been found to add the proper resiliency to the wire to hold the key levers in normal, raised position and to return them to such position after they have been operated.
- 60 In order to enable the key levers to be 65 operated with light touch and to momentarily lock the type bars in their normal or retracted position when the keys are released, I provide each key lever with a latch member N which carries the finger piece and which is pivotally connected with the front portion of the key lever at n in the manner shown. The finger piece O is mounted on an upwardly extending part n' at the front of the latch member and this 70 member has an upwardly extending arm n² at the rear which is adapted to engage an alining plate P carried by the stop rail R. The front portion of each key lever is curved upwardly, as shown, in Figure 4, 75 corresponding in form with the latch member N and each latch member N is formed with arms s, s' which engage the front portion of the associated key lever and hold the parts in proper relation with each other 80 when in operation.
- The key levers extend through a comb guide T of the usual kind which, as shown, is attached to the stop rail R in any suitable way.
- 85 Normally, of course, the front ends of the type bars rest on the stop D and the latches n² are then disengaged from the alining plate P. When a finger piece O is depressed the associated key lever is also depressed, the arms s, s' being then engaged with the front of the key lever. As soon as the finger of the operator is released from the finger piece the key lever is raised by its 90 spring and the type bar returns to normal position, its front end coming in contact with the stop or rest D. Inasmuch as the key lever moves quickly an impetus is given to the latch member which causes its front end to engage the alining plate in the manner indicated in Fig. 4. This occurs at precisely the same time that the front end of the type bar reaches the stop D and thus the type bar is prevented from rebounding. In this way any tangling or confusion 95 of the type bars is avoided. The parts are so made and adjusted that when the latch operates to hold the type bar with its front end resting on the stop D it does so only momentarily as the weight of the front of the latch or that part in front of the pivot n is sufficient to withdraw the latch and to cause the latch member to assume its normal 100 position as shown in Figure 1.
- 105 I claim as my invention:
1. In a typewriting machine key levers operatively connected with type bars and springs for holding the key levers in normal position and for returning them thereto, said springs being mounted to directly engage and slide on the key levers, and means for simultaneously or collectively adjusting the springs fore and aft of the machine.
  2. In a typewriting machine, the combination with the key levers and the type bars of a spring-carrying frame having means for adjusting it fore and aft of the machine, and springs mounted on the machine which have coiled portions and front looped portions which directly engage the key levers.

3. In a typewriting machine, the combination with the key levers and the type bars of a spring-carrying frame, means for adjusting the springs fore and aft of the machine, while in direct contact with the key levers, and means for supporting the frame and for guiding it while being adjusted which are operable from the outside of the machine frame.
- 10 4. In a typewriting machine, the combination with the key levers and the type bars of a Z-shaped spring-carrying frame, springs attached to the upper front part thereof and which are connected with the key levers, and means operable from the outside of the machine frame and connected with the vertical part of the Z-shaped frame for adjusting the spring-carrying frame fore and aft of the machine.
- 15 5. In a typewriting machine, the combination with the key levers and the type bars of a spring-carrying frame, springs thereon which engage the key levers, an arm extending rearwardly from the spring-carrying frame, a bracket attached to the machine frame, and a roller carried by said bracket with which the arm of the spring-carrying frame engages.
- 20 6. In a typewriting machine, key levers operatively connected with type bars, springs having portions which directly engage the key levers and hold said levers in normal position and return them thereto, and means for simultaneously and collectively adjusting the springs lengthwise of the levers while in engagement therewith.
- 25 7. In a typewriting machine pivoted key levers operatively connected with type bars, springs having uniform tension which hold the key levers in normal position and return them thereto and which are adjustable fore and aft of the machine longitudinally of the key levers and relatively to the pivots thereof to vary the distance of the connections between the springs and the levers from the pivots of said levers.
- 30 8. In a typewriting machine, the combination with the key levers and the type bars of a stop or rest for the type bars, and latch mechanism associated with the levers for momentarily locking the type bars in re-
- tracted position after their return from the printing point.
9. In a typewriting machine, the combination with the key levers and the type bars of a stop or rest for the type bars, and latch mechanism carried by and movable with the key levers and which engage a stationary part of the machine for momentarily locking the type bars in retracted position after their return from the printing point.
10. In a typewriting machine, the combination with the key levers and the type bars of a stop or rest for the type bars, and latch mechanism pivotally connected with the front ends of the key levers, which engage a stationary part of the machine frame and which are operated by the momentum of the key levers when returning from the depressed position to momentarily lock the type bars in retracted position after their return from the printing point.
11. In a typewriting machine, the combination with the key levers and the type bars of a stop or rest for the type bars, latches pivotally connected with the front portions of the key levers and momentarily engaging a stationary part of the machine frame, finger pieces carried by said latches, and stops on the latches engaging the key levers for limiting the movement of the latches relatively to the key levers.
12. In a typewriting machine, the combination of pivoted key levers and pivoted type bars operatively connected with the key levers, a stop or rest for the type bars when inactive, and latches pivotally connected at their rear ends with the front portions of the key levers which carry finger pieces and which are provided at their rear ends above their pivots with parts adapted to engage a stationary part of the machine frame immediately after the type bars have returned to normal from the printing point and which latches are automatically released by their own gravity as soon as the type bars come to rest and liability of rebound has passed.

In testimony whereof, I have hereunto subscribed my name.

GUSTAVE O. DEGENER.
